COMBINED PAINTBRUSH HANDLE AND
DISPOSABLE BRISTLES

Bill G. Blount, 1417 Oak Lea Drive, Irving, Tex. 75060

Filed Sept. 30, 1965, Ser. No. 87,242

Term of patent 14 years

(Cl. D9—2)

FIG. 1

FIG. 2

FIG. 3

FIG. 4

FIG. 5

FIG. 1 is a front elevational view of a combined paintbrush handle and disposable bristles showing my new design;

FIG. 2 is a side elevational view thereof;

FIG. 3 is a back view thereof;

FIG. 4 is an end view thereof;

FIG. 5 is an isometric view thereof.

I claim:

The ornamental design for a combined paintbrush handle and disposable bristles, as shown.
